UNITED STATES PATENT OFFICE.

WILLIAM B. CHAPMAN, OF JACKSON HEIGHTS, NEW YORK, ASSIGNOR TO THE CHAPMAN-STEIN FURNACE CO., OF MOUNT VERNON, OHIO, A CORPORATION OF OHIO.

CONTINUOUS PUSH FURNACE.

Application filed August 2, 1924. Serial No. 729,690.

The invention relates to a furnace of the type wherein billets or similar objects to be heated are successively fed into one end of the furnace, and pushed therethrough, until 5 they finally pass out of the furnace at its opposite or delivery end.

One object of the invention is to provide a furnace of the above nature, of such construction that the flow of the hot gases 10 through the heating chamber may be controlled to produce substantially uniform temperature conditions throughout the width of the heating chamber; in other words, to prevent the formation of localized 15 currents of hot gases at different temperatures from passing through the heating chamber in such a way as to create unbalanced temperature conditions.

Another object is to construct the furnace 20 so with regard to the air and gas which enter into combustion, that the hottest temperatures will obtain at the point required, namely, near the discharge end of the furnace.

25 The invention also aims to lead the gases to be burned into the heating chamber in a manner economical from the standpoint of space required, and in such a way as not to interfere with the room needed at the 30 discharge end of the furnace to accommodate the machinery for receiving the billets discharged therefrom.

The invention also includes certain features of construction to permit proper cleaning 35 of the flues and portways employed in the furnace, and other features of construction enabling the billets to be subjected more evenly to the effect of the heated gases.

The above and other objects and features 40 of the invention will be in part obvious and in part more specifically referred to in the description hereinafter contained, which, taken in conjunction with the accompanying drawings, discloses a preferred embodiment there- 45 of; such embodiment, however, is to be considered as merely illustrative of its principles. In the drawings:

Fig. 1 is a longitudinal vertical sectional view of a furnace constructed in accordance 50 with the invention.

Figs. 2, 3, 4 and 5 are sectional views taken respectively on lines 2-2, 3-3, 4-4 and 5-5 of Fig. 1, looking in the direction of the arrows.

55 The invention is illustrated as applied to

a furnace having an elongated heating chamber 1, and a suitable door 2 at its entrance end, through which the material to be heated is fed into the furnace. The heated gases pass the chamber 1 from left to right, as the 60 latter appears in Fig. 1, and are then led downwardly through ports 3 (Figs. 1 and 2) near the entrance end of the furnace, to a pair of conduits 4 which lead to a suitable recuperator denoted generally by numeral 65 5, whereby the heat of the spent gases may be utilized to preheat the air for combustion. It will be understood that any suitable apparatus may be employed for the above purpose, but I prefer to employ a recuperator wherein the spent gases pass back and forth horizontally past courses of hollow tiles, as indicated in Fig. 1, until finally 70 they are exhausted through flues 6 at the bottom of the recuperator. The detailed 75 construction of such a recuperator is well known, being shown for example in the United States patent to Stein #1,404,721 dated Jan. 1st, 1922, and accordingly will not be set forth at length herein, it being 80 sufficient for the purposes of the present invention to state that the incoming air passes upwardly through the recuperator 5, through vertical passages in the tiles which make up the recuperator, to a gathering chamber 7 85 located above the recuperator, and thence to a conduit 8 (Figs. 1 and 3) leading toward the delivery end of the furnace.

The billets, ingots or the like, to be heated are supported upon water-cooled skids 9, as 90 they pass through the furnace, the skids being supported near the entrance end of the furnace by a plurality of piers 10, and being approximately horizontal for the major portion of the heating chamber 1. At the 95 delivery end of the furnace the skids 9 are downwardly inclined at 11, a discharge slope being provided down which the billets will fall to a doorway 12, the door 13 of which will be opened at the proper time to permit the billets to be delivered on to a suitable conveying apparatus, as indicated diagrammatically at the left of Fig. 1 beneath door 13.

In accordance with the present invention the air and gas which enter into combustion, are led into the delivery end of heating chamber 1, through a series of ports spaced across the width of the furnace, the object being to mix the air and gas thoroughly at

the start and then introduce the mixture into the heating chamber in a manner economical from the standpoint of space occupied, and without necessitating conduits or chambers so located as to interfere with the proper handling of the billets at the discharge end of the furnace.

In the present embodiment of the invention, the gas, (for example producer gas or 10 gasified oil), is led into the furnace through a plurality of passageways 14 (Figs. 1 and 4) located beneath the incoming air conduit 8, and terminating in a plurality of gas chambers 15 disposed beneath the discharge 15 slope 11 of the furnace. The chambers 15 are preferably provided with suitable cleaning doors 16, to permit the removal of soot, dust and other accumulation therefrom.

The preheated air from conduit 8 passes 20 into an air chamber 17 (see Figs. 1 and 5) located above chambers 15 above described, and provided with a series of vertical hollow walls 18 (see Figs. 3 and 5) providing vertical portways 19 which pass downwardly 25 through the floor 22 of chamber 17 to the various gas passageways 15. Thus in effect the chamber 17 constitutes a mixing chamber for the air and gas, and the walls 18 are preferably provided with caps 20 which are 30 spaced from the upper ends of the walls at certain points to provide laterally directed ports 21, which project the gas transversely into the currents of air passing through portways formed by the space between the walls 35 18, and tend to mix the air and gas thoroughly. The combustible mixture of air and gas then rises upwardly between the caps 20 and is ignited in the discharge end of the furnace above discharge slope 11.

40 The thorough mixing of the air and gas as aforesaid enables the mixture to be quickly ignited and burned at the discharge slope 11, whereby the ingots pass through the hottest portion of the furnace just before 45 being delivered therefrom, and avoiding any cooling of the ingots which would take place if the mixture of the air and gas were not complete enough to burn until after passing along the heating chamber 1 to some extent. 50 Preferably the gas ports 21 are spaced somewhat from the discharge end walls of the furnace to prevent the flames from overheating the same.

The floor or bottom wall 22 of the chamber 55 17 is preferably inclined toward the discharge end of the furnace, providing a chute which leads to a plurality of doorways 23 between the vertical walls 18 above mentioned. Doors 24 permit any scale, dust or 60 other accumulation to be readily removed through the doorways 23 when desired. Since the gas ports 21 are laterally directed at their mouths, and located in the upper portion of chamber 17, very little dust or 65 scale will accumulate in them, but the major

portion of the accumulation will fall to the inclined floor 22 and slide down the latter to the doorways 23.

A pit 25, shown diagrammatically at the left of Fig. 1, may be employed at the discharge end of the furnace to permit ready access to the doors 16 and 24 for cleaning purposes. The billet-conveying apparatus 26 will be supported from a bridge work 27 at the discharge end of the furnace, and 70 extending across the pit 25. The cleaning doors 16 and 24, being located underneath the conveying apparatus, do not encroach upon the room needed for the latter, nor does the conveying apparatus obstruct access to 75 the cleaning doors. The air and gas portways furthermore being entirely contained within the confines of the furnace proper, do not require any extra space either at the discharge end or the sides of the furnace. 80

After rising from chamber 17, the mixture of air and gas is ignited and passes along the heating chamber 1 over a slag pit 28, which I prefer to separate from the discharge end of the furnace by a bridge wall 90 29, which is substantially lower in elevation than the horizontal portion of skids 9. Such a construction permits the gases of combustion to pass as well under as over the billets supported by the skids, and thus promotes 95 uniform heating. Furthermore, I prefer to support the horizontal portions of skids 9 above the slag pit 29 in such a way as to afford free passage of the gases of combustion underneath the skids; as shown, the 100 skids 9 are supported in this part of the furnace by means of water-cooled pipes 30 passing through the side walls of the furnace, and which afford no such obstruction to the passage of the heated gases underneath the skids as would be entailed for example by supports resting upon the bottom of the slag pit.

It will be noted that the currents of air and gas mixing in chamber 17, are ignited 110 at a point in the discharge end of the furnace near the doorway 12, with the result that when door 13 is opened, the expanding gases of combustion offset any tendency toward an inward draft of cold air through 115 the doorway 12.

The air and gas portways, being spaced across the width of the furnace, project a gaseous current into the heating chamber which naturally fills the entire cross-section 120 of the latter, and in case the hot gases tend to form localized currents of uneven temperatures, the flow of gas or air or both to any particular part of the heating chamber, may be regulated to restore uniform temperature 125 conditions. For example, either of the gas passageways 14 (Fig. 4) may be regulated to supply more or less gas to its corresponding chamber 15, by adjustment of suitable dampers indicated diagrammatically at 31; 130

and the area of the air portways formed in chamber 17 between the vertical walls 18, may be likewise adjusted by placing one or more bricks 32 (Fig. 1) upon the floor 22 5 of chamber 17, through the cleanout doors 24, to block off as much as may be desired of any of the air portways above-mentioned. Thus the amounts of air and gas supplied to the central and side portions of the heating chamber may be effectively controlled. 10 While a specific embodiment of the invention has been disclosed, it will be obvious that many changes may be made therein without departing from its principles, as 15 set forth in the appended claims.

I claim:

1. A continuous push furnace having at its discharge end, a series of alternating upwardly extending gas and air portways opening 20 into the heating chamber of the furnace from underneath, said series of portways being disposed across the width of the furnace, certain of said portways being directed laterally at their mouths to deflect their contents laterally into other portways.

2. A continuous push furnace having at its discharge end, a series of upwardly extending gas and air portways opening into the heating chamber of the furnace from underneath, said series of portways being disposed across the width of the furnace, certain of said portways being formed in upstanding hollow walls extending into a chamber, and said walls being provided with 35 caps which deflect the gaseous currents issuing therefrom laterally into other portways located in said chamber between such walls.

3. A continuous push furnace having at its discharge end a series of upwardly extending air and gas portways opening into the heating chamber of the furnace from underneath, said series of portways being spaced across the width of the furnace, a 40 slag pit associated with the heating chamber

of the furnace, skid members supported above said slag pit and downwardly inclined at the discharge end of the furnace to provide a discharge slope, and a bridge wall for said slag pit extending upwardly to a level substantially below the level of the intermediate portions of the skid members, to permit the heated gases to pass over said bridge wall and under said skid members.

4. A continuous push furnace having a plurality of gaseous fuel passageways leading to points spaced across the width of the furnace and beneath its discharge end, spaced upwardly extending fuel portways communicating respectively with said conduits, and upwardly directed air portways disposed between the fuel portways above-mentioned adapted to mix the air and gas beneath the discharge end of the furnace, and project such mixture into the discharge 65 end of the heating chamber of the furnace from underneath, one set of said portways being capped and the other set being accessible from the end of the furnace for cleaning purposes.

5. A continuous push furnace having skid members passing through its heating chamber and having at its discharge end a series of upwardly extending gas and air portways opening into the heating chamber of the 75 furnace from underneath, said series of portways being disposed across the width of the furnace and communicating with each other at a point sufficiently beneath the discharge ends of the skid members to mix the gas 80 and air beneath said skid members and cause the mixture to burn substantially at the discharge ends of the skid members.

In testimony that I claim the foregoing, I have hereunto set my hand this 11th day 85 of June, 1924.

WILLIAM B. CHAPMAN.
